MINING MACHINE

Berne Tocci-Guilbert, San Francisco, Calif.

Application January 5, 1942, Serial No. 425,609

4 Claims. (Cl. 209—44)

This invention relates to improvements in mining machines and more particularly to a combined machine for grading, classifying and concentrating the metal bearing fines from auriferous and other ores, suspended in flowing pulp.

Among the objects of the invention is the simplification of the structure and arrangement of the various parts so that they may be combined in a compact machine.

Another object is the improvement of the means by which the concentrates are removed from the classified ore, thus raising the combined efficiency of the units through which the material passes.

Another object is the provision of a machine of this character, adapted to be moved over rough and rugged terrain and having means for leveling the ore concentrating mechanisms.

Another object is reducing to the minimum the cost of transporting unproductive material, to the machine.

A further object is the mobilization of the recovery apparatus so that the machine may be taken to the material.

Other objects and advantages will appear as the description proceeds.

In this disclosure the term "material" is intended to define auriferous ores containing gold, silver, platinum and other metallic values associated with quartz, gravel, and other base material either milled or found in a comminuted state in nature, colloquially known as "pay dirt."

The present mobile machine is particularly designed to work natural placer deposits and tailings resulting from hydraulic and dredging operations. One great advantage is that the machine can be taken to the material and the transportation of unproductive material avoided. But it is to be understood that the combination of units may be permanently installed as a mill to handle comminuted ore adapted to processing according to the present invention.

In this specification and the accompanying drawings the invention is disclosed in its preferred form. But it is to be understood that it is not limited to this form; because it may be embodied in modifications within the spirit of the invention as defined in the claims following the description.

In the three sheets of drawings:

Fig. 1 is a side elevation of a mining machine constructed and combined in accordance with this invention.

Fig. 2 is a view of the opposite side of the machine, partially in vertical section.

Fig. 3 is a plan view of the hutch leveling frame pivoted within the main frame of the machine.

In detail the construction illustrated in the drawings, referring first to Figs. 1 and 2, comprises the rectangular main frame A, having the side beams 1, 2, and the end beams 3, 4. This main frame is cross braced beneath by the X frame 5 attached to the four corners for greater rigidity.

The superstructure comprises the uprights 6, 7, 8 and 9, 10, 11, fixed to the main frame and suitably cross braced. The subframe 12, 13 is fixed to these cross braces and provides a rigid mounting for the classifying shaker screen unit B.

The conventional rotary trommel C is suitably mounted in the superstructure and driven by the motor unit D, beneath the platform E forming the top of the superstructure.

The receiving hopper F extends outwardly from the superstructure and is supported by the standards 14, 15 attached to the main frame A. The inclined bottom 16 of the hopper delivers into the upper end of the trommel C. The semicircular guard G extends around and beneath the lower diameter of the perforated portion of the trommel.

In the present instance the trommel has three sections H, I, J, of varying size perforations respectively, ranging from fine ($\frac{1}{4}$ ") at H, medium ($\frac{3}{8}$ ") at I, and coarse ($\frac{1}{2}$ ") at J. The sizes of the perforations can be chosen according to the results desired. These sections are defined by the annular flanges 17, 18, 19, 20, which operate in proximity to the guard G to separate the material graded by the several sections of the trommel. The guard G is provided with the spouts 21, 22, 23, interspaced beneath the several sections of the trommel respectively.

These spouts discharge their respectively graded material into the classifying shaker unit B. This unit consists of a boxlike structure 24 closed at the forward end and overflowing at the rear into the disposal trough at 25, which discards the unwanted material. This box 24 is supported on a series of leaf spring supports on each side such as 26, 26 having their lower ends fixed to the subframe 12, 13. This box 24 is reciprocated longitudinally by flexible leafspring arms engaging eccentrics driven by a variable speed motive unit 28, see Fig. 1. These reciprocations are counterbalanced by the oblique adjustable coil springs such as 27, 27 on its oppo-

site sides. This particular spring mounting and drive imparts a highly resilient vibratory action to the classifying unit B. Three sections of co-planal screens of progressively larger mesh are set within the box 24 to form a submerged deck therein. These screen sections are vertically aligned with the perforated sections of the trommel C above.

The triangular hoppers 28, 29, 30 form the bottom of the box 24, beneath their respective screen sections, such as 24'. These hoppers have the gates 31, 32, 33, pivoted thereon to control the volume of material flowing downward therefrom. These hoppers also have the side outlets 34, 35, 36, see Fig. 2, respectively discharging into the disposal trough 25', to drain off the excess water to prevent the hoppers overflowing.

The hatches, or other concentrating means P, Q, R, are located immediately below the discharge gates 31, 32, 33 respectively. It is important that these hatches be maintained level and plumb, which is an important feature of this invention.

The hutch leveling frame shown in Fig. 3, consists of the sides 34, 35 and the ends 36, 37 properly joined to make a rigid structure. Each hutch has its separate pairs of transverse bars 38, 39-40, 41, respectively, extending between the sides 34, 35. These sides are provided with the trunnions 44, 45, engaging the bearings mounted upon the side beams 1, 2 of the main frame A. The end 36 of the leveling frame has the arm 46 pivoted to the threaded spindle 47 engaging a bevel gear 48 on the bracket 49 mounted upon the adjacent end 4 of the main frame. The bevel gear is driven by a pinion on the end of the shaft 50 which has the handwheel 51 located in convenient reach on the side of the main frame. Turning the handwheel raises or lowers the end of the leveling frame for horizontal longitudinal adjustment of the leveling frame with respect to the ground angle of the main frame A. If desired the trunnions 44, 45, may be made vertically adjustable on the main frame A, for lateral leveling of the hutch frame. In the present instance each hutch is independently leveled laterally.

The hatches P, Q, R, are alike in structure and it is deemed sufficient to describe only one in detail. The hutch has the boxlike upper portion 52, and the tapered lower portion 53, with the outlet gate 53' on the lower end, see Fig. 1. The hutch is suspended in the surrounding tilting frame 54 having the trunnions 55, 56 in axial alignment on the opposite sides thereof which engage their respective bearings on the side rails of the roller truck frame 57. The truck frame 57 has the flanged rollers, such as 57' traveling on the cross bars 36-41, for instance. Means are provided for locking the hatches in leveled position.

The hutch has the upper tier 52 hinged at 59 to the upper edge of the hutch. A gasket is interposed between the top edge of the hutch and the lower edge of the tier and adapted to be compressed by the screw clamps, such as 60 to make a water tight joint at this point. The bottom of the tier 52 consists of the screen 61, located above the gasket level, see Fig. 1.

A series of compartments is formed above this screen by the bisecting partitions 62, 63, extending upwardly above the screen 61. The front end of the tier overhangs at 64, to receive the discharge from the hopper such as 28 above. The bottom of this overhang 64 is about on the level

with the top of the compartments formed by the partitions 62, 63.

These compartments are filled level with steel pellets 65, about $\frac{1}{8}$ of one inch in diameter. The incoming material flows across the tops of these pellets and the fines suspended therein descend into the interstices between the pellets and into the sump formed by the lower portions of the hutch 53. The discarded particles flow into the inclined trough 66 overhanging the opposite side of the hutch, and are discharged into the disposal trough 25'.

The upper stratum of water in the hutch, below the screen forming the bottom of the tier, is pulsated in an upward direction only. This upsurge of water through the screen 61 lifts the lighter particles of detritus and facilitates the descent of the heavier fines into the hutch. Each hutch is provided with a pulsator 67 immediately below the screen, from which the incoming water through the hoses 68, 69 is intermittently discharged upwardly, without disturbing the quiescent water in the hutch below the pulsator. This quiescent stratum enables the fines, such as float gold, to precipitate without the levitating effect of agitation. For further particulars regarding this particular type of hutch see my copending application of even date bearing Serial Number 425,610. However, it is characteristic of concentrating hatches and jigs that they should be level to operate efficiently. It is an important feature of the present invention to provide such leveling means regardless of the particular form of concentrating means, such as the hatches illustrated.

In this disclosure the machine is mounted upon the conventional traction belt trucks S, S, at the rear end of the main frame A. The front end of the frame is supported upon the pivotal truck T, of similar type, to facilitate turning the machine, that is adapted to be towed by a tractor. To facilitate transportation, the trommel C, including its base frame, can be unbolted from the superstructure, to reduce the overhead clearance, when carried by a trailer or railway gondola.

The combined machine on the main frame A, can be mounted upon a barge in dredger practice, by omitting the traction trucks S-T. Or it may be mounted upon a permanent foundation for mill practice, wherein the material is brought to the mill.

This invention operates substantially as follows: The material is elevated and dumped into the hopper F, in accordance with common drag line practice; which also scrapes a path for the advancement of the machine. It is desirable to include a tractor "bulldozer" in the outfit to prepare the way for the dragline unit.

The material gravitates from the hopper F, into the upper end of the inclined trommel C, which usually contains helical vanes to retard the movement of the smaller particles of material while permitting the larger rocks and pebbles to roll through the trommel onto the conventional endless belt stacker U for disposal behind the machine.

The trommel has an elevated water pipe 16' extending its length which jets water with considerable force against the material passing through the trommel. The desirable particles of material are graded and passed by the perforated sections H, I, J, assisted by a liberal flow of water through the hopper F and the trommel C.

The finer particles graded by the section H of the trommel descend into the guard G and are discharged through the spout 21 into the first

section of the shaker screen unit B, which has the finest mesh. From thence the selected material passes into the tier 52 of the first hutch P.

The material graded by the trommel sections I, J, take a similar path through the spouts 22, 23, the progressively sized meshes of the classifying screen unit B, and into the tiers of the hutches Q, R, respectively. The peculiar longitudinal reciprocations and vertical vibrations of the unit B, cause the flowing particles of the material from the trommel C to travel across the screens therein and find their way through the meshes thereof, or be discharged from the end of the screen unit B if too large, and into the disposal trough 25', to be disposed of at the rear of the machine.

In the present instance there is at all times a liberal flow of water through the perforation of the trommel C, through the shaker screen unit B and into and across the pellet level of the several hutches P, Q, R. This water may be impounded in ponds for reuse for economy, with the further advantage that colloidal or float gold or other values in suspension may be saved in their re-passage through the machine.

Periodically the machine is shut down for the cleanup. The flexible hoses 68, 69 are uncoupled, and the hutch is rolled laterally on its mobile truck on the cross bars, such as 36-41, to the side of the main frame A. The removable tray V, see dotted lines, is placed in position on the side beam 1. The tier 52, is swung upward on the hinges 59, and the contents of the tier, including the pellets 65, is dumped into a screen laid across the top of the tray V, the mesh of the screen being finer than the diameter of the pellets. The concentrates impounded in the interstices between the pellets flow from the tray into a tub beneath for recovery. This enables the cleaning of the meshes of the screen 61, which supports the pellets. The pellets are also freed of values or other matter accumulated thereon during a run. The tier and the hutch are then restored to operative condition. When the concentrates accumulate in the bottoms 53 of the hutches to an obstructive extent, they are drained off through the gates 53', and processed by amalgamation or otherwise, to separate the metallic values from the detritus.

The trommel C is more or less conventional. The preferred shaker classifying screen B illustrated is known in the art as the Symons screen, which is covered by a number of patents, and is included only as a suitable unit in the present combination. Other forms of classifiers are available as substitutes to perform the same function.

The function of the trommel and the shaker are preliminary to the work of the hutches, and they may be chosen or modified in accordance with the nature of the material being processed.

Broadly stated the present invention resides in the combination of elements, some of which are old. The novel contributions relate particularly to the mobile frame with hutch leveling means.

Having thus described this invention, what is claimed and desired to secure by Letters Patent is:

1. A mobile mining machine including a main frame having a superstructure thereon, traction means supporting said frame; a trommel assembly mounted upon said superstructure; a stacker pivoted on said main frame in operative relation to the discharge from said trommel; an ore classifier below and fed from said trommel; a leveling frame pivotally mounted on said main frame; a truck movable on said leveling frame; ore concentrating means mounted below said classifier on said truck on pivots whose axes are transverse to the axes of the leveling frame pivots; and means for locking said concentrating means in adjusted position.

2. A mobile mining machine including a main frame; traction means supporting said frame; a leveling frame pivotally mounted on said main frame; a truck transversely movable on said leveling frame; pivots on said truck with their axes transverse to the axes of the pivots supporting said leveling frame; and ore separating hutches mounted on the pivots on said truck.

3. A mobile mining machine including a main frame; traction means supporting said frame; a leveling frame pivotally mounted on said main frame; transverse tracks on said leveling frame; a truck movable on said tracks; and ore separating hutches mounted on said truck in such a manner that said hutches can be leveled with respect to the plane of said main frame.

4. A mobile mining machine including a main frame; traction means supporting said frame; a superstructure on said main frame; a trommel assembly mounted upon said superstructure; a stacker pivoted upon said main frame in operative relation to the discharge end of said trommel; an ore classifier below said trommel; a leveling frame having trunnions pivotally mounted transversely on said main frame; means for swinging said leveling frame relative to said main frame on said trunnions; and ore concentrating hutches mounted on said leveling frame below said classifier.

55 BERNE TOCCI-GUILBERT.
